(57) **CLAIM**

The ornamental design for a keyboard, as shown and described.

DESCRIPTION

FIG. 1 is a perspective view of a keyboard showing our new design;

FIG. 2 is a rear perspective view thereof;

FIG. 3 is a rear perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is an enlarged view of an indicated portion of FIG. 1;

FIG. 11 is an enlarged view of an indicated portion of FIG. 3;

FIG. 12 is an enlarged view of an indicated portion of FIG. 3; and,

FIG. 13 is a rear perspective view thereof showing a state that a connecting member is rotated and has not been connected to a screen.

The dot-dashed broken lines represent a boundary of the keyboard and form no part of the claimed design, all of the remaining broken lines represent environment only and form no part of the claimed design.
